UNITED STATES PATENT OFFICE.

CHARLES McARTHUR, OF WINNIPEG, MANITOBA, CANADA, ASSIGNOR OF ONE-HALF
TO MYLES McARTHUR, OF WHITEWOOD, CANADA.

SHOCKING-MACHINE.

1,056,431.

Specification of Letters Patent. Patented Mar. 18, 1913.

Application filed December 19, 1910. Serial No. 598,209.

To all whom it may concern:

Be it known that I, CHARLES McARTHUR, of the city of Winnipeg, in the Province of Manitoba, Canada, have invented certain new and useful Improvements in Shocking-Machines, of which the following is the specification.

My invention relates to shocking machines, and the object of the invention is to provide a shocking machine attachable to the ordinary binding machine which will receive the sheaves passed from the binder deck, collect them in the form of a shock and deposit the shock so formed on the ground, such machine being easily operated, compact, and having great capacity.

A further object of the invention is to provide a shocking machine which can be shifted backwardly and forwardly relative to the binding machine so as to always receive the sheaves evenly regardless of the length of the sheaves.

The invention consists essentially in the novel arrangement and construction of parts as hereinafter more particularly described, reference being had to the accompanying drawings in which,

Figure 1 is a plan view of the complete machine. Fig. 2 is an end view of the same showing means for shifting the deck and adjoining parts. Fig. 3 is an enlarged detailed plan view of the shocking machine carriage wheel and adjoining parts. Fig. 4 is a front view of the cam controlling the fingers. Fig. 5 is a side elevation of the arm controlling the movement of the basket and the gears operating the same. Fig. 6 is an enlarged vertical sectional view through the frame adjoining the butter. Fig. 7 is a front view of the shiftable part of the binder with the adjoining portions of the shocker. Fig. 8 is a plan view of the binder frame adjoining the shocking machine. Fig. 9 is an enlarged detailed view of the means for driving the attachment drive shaft, and Fig. 10 is an enlarged detailed sectional view through a second bearing for the attachment drive shaft.

In the drawings like characters of reference indicate corresponding parts in each figure.

a represents the binder frame supplied

with the usual cross bars *b* and *c* which carry the bull wheel 1 above which is located the usual deck 2 and the elevator frame 2', the deck being provided with the binding attachment 3 which carries the discharge arms 4 carried by a rotatable shaft 4'. The deck 2 is slidably secured to the upper end of the elevator frame at *d*, and has the lower end fitted with the under cross bars *e* slidably mounted on an angle iron support *f* carried at one end by a bracket *g* secured to the frame and at the other end by an extending beam *h* fastened to the frame.

i is a brace bar passing between the binder frame and the elevator frame and supporting a crank shaft *j* having the end thereof connected by a suitable link *k* to the rear end of the cross bar *e*.

l is a chain wheel rotatably mounted in a bearing *m* secured to the brace bar *i*, and *n* is a bearing piece rotatably mounted in the downwardly extending portion of the binding attachment 3.

o is a square drive shaft passing through the bearing *n*, and the bearing *m*, which shaft is held against longitudinal displacement by the disk *p* and the collar *q* adjoining the bearing *n*. The opposite end of the shaft is free to slide through the bearing *m* when the deck and attachment are shifted by the operator turning the crank rod in a manner which will cause the link to pull the cross bar *e*. The shaft can, however, be driven in any shifted position by the chain wheel *l* which is tied to the bar *i* as above described. The disk is supplied with an arm *r* connected by a rod *s* with the disk *t* fixed on the forward end of the shaft 4'.

It is here to be understood that although the above parts are described in detail, yet I lay no claim to them, as they are at present employed on binding machines. I only introduced this detailed description so that the manner in which the shocker frame can be shifted backwardly and forwardly with the deck and attachment can be clearly understood. Once this is understood my shocking machine can be readily connected up with the various forms of shifting mechanisms now appearing on binding machines. It is to be understood that the deck and attachment is shifted in a binder to accommo-

date the knotter, it being always desirable to have the sheaf tied more or less centrally whether the crop be heavy or light.

5 represents the shocking machine frame 5 which is more or less rectangular in plan view and is supplied at the outer side with a cross bar 6 formed from angle iron which bar supports the parts shortly to be described. The outer side of the frame 5 is 10 carried by a shaft 7 on which is mounted the combined carriage and drive wheel 8, the wheel being free to turn on the shaft. The inner end of the frame 5 is supported by a link 9 which is permanently secured at 9° to the deck or other such shiftable part, and 15 pivotally secured at 9° to the frame 5. A rear link 9' is also permanently secured in a like manner to the deck or other shiftable part and pivotally to the frame 5.

20 10 is a vertically directed plate secured firmly to the bar 6 and provided centrally with a bearing for a short shaft 11, which shaft supports a second turnable plate 12 to the upper and lower edges on which 25 are secured upper and lower sets of similar arched fingers 13 forming a sheaf receiving and shock forming basket. The fingers of the upper set are connected permanently to a common horizontally disposed cross rod 30 14, which rod is carried in suitable bearings formed on the plate. The fingers of the lower set are also united to a common horizontally disposed cross rod 15 likewise mounted in bearings carried by the plate.

35 16 and 17 are arms secured to the cross rods 14 and 15 respectively, and extending rearwardly toward the plate 10 where they are received within a groove 18 formed in a cam 19 fixed on the plate 10. The groove 40 is constructed so that when the plate 12 is turned from the position shown in Fig. 2 to the vertical position, that is, a quarter revolution, the upper set of arms 13 are im- 45 mediately closed and remain closed while the lower set of arms are kept closed until the quarter turn is practically complete, at which instant they are quickly swung open. This construction is provided so that the shock formed from sheaves deposited be- 50 tween the fingers will be held tightly by the fingers while they are turning and released so as to fall on to the ground just as the quarter turn already mentioned is completed. The groove in the cam is further 55 formed so that upon the plate being turned a further quarter turn, that is, to complete a half turn, the fingers remain in the positions to which they were previously forced to deposit the shock. In this connection it 60 is well to understand that the plate is turned forwardly by gears shortly explained, that is, in the direction in which the machine is progressing. The shaft 11 is supplied with a pinion 20 which is designed to mesh with

65 a gear wheel 21 located on the shaft 7 and adjoining the carriage wheel. A spring 22 is interposed between the hub of the carriage wheel and the face of the gear wheel tending always to keep the male and female members of a clutch 23 out of contact.

70

24 is a bell crank carried in suitable brackets extending from the binder frame, which crank is connected to a link 25 passing to a bell crank 26 pivoted at 27 to the frame. The bell crank is supplied with a 75 forked end which operates in a groove 28 formed in a wheel 29 connected to the inner face of the gear wheel 21. A rod 24' is attached to the bell crank 24 and passes within convenient range of the operator on the 80 binder so that when he desires the plate carrying the fingers to turn he has only to pull the rod, which motion operates the bell crank and engages the clutch members.

85

In order to stop the rotation of the plate 85 carrying the fingers automatically is provided the following attachment—a collar 30 is permanently secured to the wheel 28, which collar has the end thereof terminating in a rectangular piece 31, which rectangular piece is adapted to pass into and 90 out of a more or less rectangular notch 32 formed in the adjoining member 6 carried by the frame 5, the notch being at the same length as the length of the rectangular end 95 piece. With this arrangement it will be seen that as soon as the clutch members are engaged the end piece 31 turns, being free of the notch and riding on the adjoining edge of the frame. However as soon as the 100 gear wheel 21 and consequently the end piece 31 has turned sufficiently far to allow the end piece to slip into the notch the clutch members will be thrown out of engagement by the action of the spring 22. This will 105 occur every half revolution as will be apparent.

100

33 is a butter extending across the frame and carried by suitable blocks 34 arranged between channel iron pieces 35 located on 110 the frame. Springs 36 pass between the butter and the frame, which springs hold the butter normally in the position shown in Fig. 1 of the drawings. A cord 37 passes from the rear of the butter over pulleys 38 and 39 located on the frame to a crank 40 carried by a gear wheel 41 rotatably mounted on the side of the plate 10. The gear wheel 41 meshes with a larger gear wheel 42 secured to the shaft 11 which shaft carries 120 the gear wheel 20 meshing in turn with the gear wheel 21 carried by the shaft 7. The above parts are constructed so that for one revolution of the shaft 11 the crank is swung a half turn. Accordingly the butter 125 33 is pulled backwardly each time the plate 12 swings and is forced back by the springs. 43 is a guide plate located on the inner

side of the frame, that is, adjoining the deck. The guide plate is bent so that it is concentric to the shaft 4' and adapted to direct the sheaves passed over the deck to the 5 fingers 13, the discharge arms 4 in their rotation forcing the sheaves successively over the guide plate.

The operation of the machine is as now described assuming the parts in the position 10 as shown in Fig. 2 of the drawings and the machine advancing. The sheaves passed over the deck are deposited between the fingers 13 by the discharge arms 4, it being noticed that the upper set of fingers are 15 raised. When the operator considers that a sufficient number of sheaves have been placed between the fingers to form a proper shock, he draws the rod 24', which motion causes the clutch 23 to engage. Owing to 20 the construction of the cam the then upper fingers 13 close down and grasp the sheaves tightly. As soon as the basket has been turned a quarter revolution the rear set of 25 fingers is released due to the construction of the cam sufficiently to allow the shock to drop to the ground and the fingers swing clear over the top of it as the machine advances, the set of fingers which were originally under coming to the top and taking the 30 open position, while the other set of fingers are ready to receive the sheaves deposited from the deck, it being understood, as already explained, that the clutch 23 is thrown out automatically as soon as every 35 half revolution is completed.

What I claim as my invention is:

1. The combination comprising a suitable rectangular frame having an open side, a vertically disposed stationary plate mounted 40 on the frame, a rotatable shaft carried by the plate, means for rotating the shaft, a second plate secured to the shaft and rotatable therewith, opposing sets of fingers pivotally secured to the opposite edges of 45 the rotatable plate, a cam carried by the stationary plate and arms connected to the fingers and having their ends operating in the cam whereby the fingers are moved toward or away from each other when the 50 plate is rotated, as and for the purpose specified.

2. The combination with a binding machine, the binder deck, the discharge arm and the shiftable attachment carrying the 55 discharge arm, of a rectangular frame having an open side secured to the shiftable attachment aforesaid at one side and mounted on a suitable carriage wheel at the opposite side, a stationary vertically disposed plate 60 secured to the frame and adjoining the carriage wheel, a rotatable shaft mounted in the plate and rotated by the carriage wheel, a second plate secured permanently to the shaft and rotatable therewith, opposing sets

of fingers pivotally secured to the latter 65 plate, arms extending from the fingers and a cam secured to the stationary plate and receiving the arms, as and for the purpose specified.

3. The combination with a binding machine the binder deck, the discharge arms and the shiftable attachment carrying the discharge arm, of a rectangular frame having an open side secured to the shiftable attachment aforesaid at one side, a carriage 75 wheel rotatably mounted on a suitably disposed shaft secured to the opposite side of the frame, a drive gear on the said shaft and adjoining the carriage wheel, clutch members carried by the drive gear and the carriage 80 wheel, means for throwing the clutch members into and out of clutch, a stationary plate mounted on the frame and adjoining the carriage wheel, a horizontally disposed short shaft rotatably mounted in the plate, 85 a pinion located on the shaft and driven by the drive gear aforesaid, a plate permanently secured to the short shaft and rotatable therewith, opposing sets of fingers pivotally secured to the opposite sides of the 90 rotatable plate, arms secured to the fingers and extending therefrom, and a cam carried by the stationary plate and receiving the extending ends of the arms, as and for the purpose specified. 95

4. The combination with a binding machine, the binder deck, the discharge arm and the shiftable attachment carrying the discharge arm, of a rectangular frame having an open side secured to the shiftable attachment aforesaid at one side, a carriage wheel rotatably mounted on a stationary shaft secured to the frame at the opposite side, a drive gear rotatably mounted on the shaft, clutch members carried by the drive 100 gear and the carriage wheel, means for throwing the clutch member into engagement, means for automatically throwing them out of engagement at a predetermined instant, a stationary vertically 105 disposed plate located on the frame and adjoining the carriage wheel, a horizontally disposed short shaft rotatably mounted in the stationary plate, a pinion secured to the shaft and operated by the 110 drive gear, a plate fixed on the opposite end of the short shaft and rotatable therewith, opposing sets of arched fingers pivotally secured to opposing edges of the rotatable plate, arms extending from the fingers, a 115 cam located on the side of the stationary plate and receiving the extending ends of the arms and a guide plate carried by the frame and adjoining the deck adapted to direct the sheaves deposited from the deck 120 to the fingers, as and for the purpose specified. 125

5. The combination with the binder deck

and the shiftable binding attachment carrying the discharge arms, of a shocking machine adjoining the binder and extending links permanently secured to the shocking machine directly and swingably secured to the shiftable binding attachment of the binder, as and for the purpose specified.

Signed at Winnipeg, in the Province of Manitoba, this 3rd day of September, 1910.

CHARLES McARTHUR.
